US00D918832S

(12) **United States Design Patent** (10) Patent No.: **US D918,832 S**
Shen et al. (45) Date of Patent: **** May 11, 2021**

(54) **BATTERY**

- (71) Applicant: **ZEBRA TECHNOLOGIES CORPORATION**, Lincolnshire, IL (US)
- (72) Inventors: **Mu-Kai Shen**, Taipei (TW); **Edward M. Voli**, East Setauket, NY (US); **I-Heng Tsai**, Taipei (TW); **Man-Ching Yen**, Taipei (TW)
- (73) Assignee: **Zebra Technologies Corporation**, Lincolnshire, IL (US)
- (**) Term: **15 Years**

(21) Appl. No.: **29/752,231**

(22) Filed: **Sep. 25, 2020**

Related U.S. Application Data

- (63) Continuation of application No. 29/670,720, filed on Nov. 19, 2018, now Pat. No. Des. 900,021.

Primary Examiner — Nathaniel D. Buckner

(57) **CLAIM**

We claim the ornamental design for a battery, as shown and described.

DESCRIPTION

FIG. 1 is a front perspective view of an example battery; FIG. 2 is a rear perspective view thereof; FIG. 3 is a top view thereof; FIG. 4 is a bottom view thereof; FIG. 5 is a first side view thereof; FIG. 6 is a second side view thereof; FIG. 7 is a front view thereof; and, FIG. 8 is a rear view thereof. The broken lines in the figures depict portions of the battery which form no part of the claimed design.
